To all whom it may concern:

Be it known that we, Leland H. Snyder and William L. Wiser, citizens of the United States, and residents of the city of Chicago, in the county of Cook and State of Illinois, have invented a new, original, and ornamental Design for a Massaging Device, or similar article, of which the following is a specification, reference being had to the accompanying drawing forming a part thereof.

On the drawing:

Figure 1 is a side elevation of a massaging de-
vice, showing our new design.

Figure 2 is a bottom plan view of the same
device.

We claim:

The ornamental design for a massaging device
or similar article, as shown.
